UNITED STATES PATENT OFFICE.

ALBERT T. LOFTSGAARDEN, OF POWELL, WYOMING.

DOOR-CLOSER.

1,223,408.

Specification of Letters Patent.

Patented Apr. 24, 1917.

Application filed January 11, 1916. Serial No. 71,492.

To all whom it may concern:

Be it known that I, ALBERT T. LOFTSGAARDEN, citizen of the United States, residing at Powell, in the county of Park and State of Wyoming, have invented certain new and useful Improvements in Door-Closers, of which the following is a specification.

My present invention has relation to spring-actuated means for closing hinged doors.

The object of the invention is to provide a simple, inexpensive and easily installed device, designed more particularly for use in combination with a screen door, at the outer side thereof, and constructed and arranged in such manner that the spring is put under tension by the opening of the door, and serves when the door is closed, to exert a leverage against and thereby promptly close the door.

Other objects and advantages of the invention will be fully understood from the following description and claims when the same are read in connection with the drawings, accompanying and forming part of this specification in which:

Figure 1 is a perspective view showing the device constituting the best practical embodiment of my invention of which I am cognizant, as applied to a screen door and the casing thereof.

Fig. 2 is an enlarged horizontal section with the device in plan.

Fig. 3 is an enlarged section, taken in a plane through the spring and between the arms of the device and the door.

Similar numerals of reference designate corresponding parts in all of the views of the drawings.

The door 1 may be and preferably is of conventional construction, and is hinged in the ordinary well known manner to the casing 2.

My novel door closer comprises brackets 3 and 4, fixed to the door-casing and door, respectively, and having outwardly-directed, horizontally-disposed flanges 5, arms 6 and 7 pivotally connected together at 8 and pivotally connected at their outer ends to the flanges 5 of the brackets 3 and 4, respectively, and a retractile spring 9 interposed between and connected to the outer side of the door 1 and the arm 7 at an intermediate point in the length of the latter. It will also be observed that the arm 7 is provided

with an inner end portion 10 which extends beyond the pivot point 8 and is constructed with a view to bringing up against the outer edge of the arm 6, thereby obviating the possibility of the arms 6 and 7 being alined 60 and the spring located in improper position on the door.

In the present and preferred embodiment of my invention and for the sake of attaining lightness, cheapness and strength, each 65 of the arms 6 and 7 is formed of a single piece of sheet-metal bent upon itself with the bight 11 of the bend outermost or remote from the door as shown. The outer end portions of the arms are bifurcated to 70 straddle the flanges 5 of their respective brackets 3, 4, and the inner end portion of the arm 6 is bifurcated for the reception and play of the extended end portion 10 of the arm 7. 75

One end of the spring 9 is connected in any approved manner to the outer side of the door 1, and the other end of the spring is suitably secured on a nut 12. The said nut 12 receives a threaded bolt 13 which takes through one of a series of apertures 14 in the bight of the arm 7 and has its head 15 opposed to the outer side of the said bight. The nut 12 and bolt 13, arranged as stated, constitute a highly efficient regulating means for the spring as will be readily appreciated when it is stated that mere turning of the bolt 13 will be attended by tightening or loosening of the spring according to the direction in which the bolt is turned. 80 The plurality of holes 14 is provided in order that the spring may be positioned as various conditions require relatively to the arm 7. 85 90

In the practical use of my novel device, it will be manifest that opening of the door 1 will be attended by flexing of the connected arms 6 and 7 and expansion of the spring 9, and that consequently when the opened door is released the spring by contracting to its 100 normal state will operate to promptly return the arms 6 and 7 to their normal positions and by so doing will securely close the door; also, that normally the spring-controlled device will serve to yieldingly hold the door 105 in closed position as is desirable.

The arrangement of my improvement at the outer side of the door and adjacent to the hinged edge thereof, is materially advantageous inasmuch as it precludes the pos- 110

sibility of the improvement interfering with the usual manipulation of the door.

Having described my invention, what I claim and desire to secure by Letters Patent, is:

1. A spring-actuated door-closing device, comprising brackets adapted for connection to a door casing and a door, respectively; said brackets having outwardly extending flanges, an arm formed of a strip of sheet-metal bent upon itself and having a bifurcated outer end portion receiving and pivoted to the door-casing bracket, an arm formed of a strip of sheet-metal bent upon itself and having a bifurcated outer end portion receiving and pivoted to the flange of the door bracket; the said arms being pivoted together adjacent to their inner ends, and one arm having an inner extended end portion movable in a bifurcation of the other and adapted to bring up against the back edge of such other, a retractile spring adapted at one end for connection to a door, and a connection between the other end of said spring and the arm complementary to the door-bracket; said connection being ar-

ranged in an aperture in the bight of the arm.

2. A spring-actuated door-closing device, comprising brackets adapted for connection to a door casing and a door, respectively, an arm formed of a strip of sheet-metal bent upon itself and pivoted at its outer end to one bracket, an arm formed of a strip of sheet-metal bent upon itself and pivoted to the other bracket; the said arms being pivoted together adjacent to their inner ends, and one arm having an inner extended end portion movable in a bifurcation of the other and adapted to bring up against the back edge of such other, a retractile spring adapted at one end for connection to a door, and a connection between the other end of the spring and one arm; said connection being arranged in an aperture in the bight of the arm.

In testimony whereof I affix my signature in presence of two witnesses.

ALBERT T. LOFTSGAARDEN.
